UNITED STATES PATENT OFFICE.

AUGUST T. BAHR, OF SPRINGFIELD, ILLINOIS.

DESIGN FOR A CORD-HOLDER.

48,701.

Specification for Design.

Patented Mar. 14, 1916.

Application filed November 8, 1915. Serial No. 60,451. Term of patent 7 years.

To all whom it may concern:

Be it known that I, AUGUST T. BAHR, a citizen of the United States, residing at Springfield, in the county of Sangamon and State of Illinois, have invented a new, original, and ornamental Design for a Cord-Holder, of which the following is a specification, reference being had to the accompanying drawing, forming part thereof.

The drawing is a perspective view of a cord holder embodying my invention.

I claim:

The ornamental design for a cord holder as shown.

Signed at Springfield, Illinois, this 4th day of November, 1915.

AUGUST T. BAHR.

Witnesses:

Roy G. TROXELL,
W. C. HOLMES.
